UNITED STATES PATENT OFFICE.

GEORG WEISS, OF CHICAGO, ILLINOIS.

DESIGN FOR A LAMP-BODY.

SPECIFICATION forming part of Design No. 29,365, dated September 20, 1898.

Application filed August 11, 1898. Serial No. 688,399. Term of patent 7 years.

To all whom it may concern:

Be it known that I, GEORG WEISS, a citizen of the United States, residing at Chicago, in the county of Cook and State of Illinois, have 5 invented and produced a new and original Design for a Lamp-Body, of which the following is a specification, reference being had to the accompanying drawings, forming part thereof.

10 Figure 1 is a view in elevation of a lamp embodying my design. Fig. 2 is a plan view thereof.

15 As shown in the drawings, the leading and characteristic feature of my design consists in a cylindrical base A, a spherical reservoir

B, mounted thereon and connected therewith by means of a neck B', and a hood C, supported in front of the spherical portion B.

Having described my invention, what I claim as new, and desire to secure by Letters 20 Patent, is—

The design for a lamp-body as herein shown and described.

In witness whereof I have hereunto subscribed my name in the presence of two wit- 25 nesses.

GEORG WEISS.
